DESIGN FOR A COMBINED SINK AND CABINET

Jacques Stanitz, Warren, Ohio, assignor to Mullins Manufacturing Corporation, Salem, Ohio, a corporation of New York

Application September 26, 1945, Serial No. 122,353

Term of patent 7 years

(Cl. D33—19)

To all whom it may concern:

Be it known that I, Jacques Stanitz, a citizen of the United States, residing at Warren, in the county of Trumbull and State of Ohio, have invented a new, original, and ornamental Design for a Combined Sink and Cabinet, of which the following is a specification, reference being had to the accompanying drawing forming part thereof.

The application is a continuation in part of my copending application Serial No. D-116,639, filed December 1, 1944. The figure is a perspective

view of a sink and cabinet showing my new design; the rear, not shown, presenting substantially a plain surface, and the end, not shown, presenting substantially the same appearance as the end that is shown. The characteristic features of my design are shown by means of full lines in the drawing.

I claim:

The ornamental design for a combined sink and cabinet, substantially as shown and described.

JACQUES STANITZ.
